CLAIM

The ornamental design for an offset alignment device, as shown and described.

DESCRIPTION

FIG. 1 is a top perspective view of an offset alignment device showing my new design;

FIG. 2 is a side elevation thereof;

FIG. 3 is a top perspective view of bottom element of the claimed design shown separately for ease of illustration;

FIG. 4 is another perspective view thereof shown inverted;

FIG. 5 is a side elevation thereof;

FIG. 6 is a side elevation of the upper element shown separately for ease of illustration;

FIG. 7 is a top perspective thereof; and,

FIG. 8 is another perspective view thereof shown inverted.
